CLAIM

The ornamental design for a truck camo shirt, as shown and described.

DESCRIPTION

FIG. 1 is a front elevation view of a truck camo shirt, showing my new design; and,

FIG. 2 is a detailed front elevation view thereof.

The evenly spaced broken lines shown in the drawings illustrate surface ornamentation that forms no part of the claimed design. The broken dashed lines showing the bounds for enlargement form no part of the claimed design. The remaining broken dashed lines shown in the drawings illustrate portions of the truck camo shirt that form no part of the claimed design.
